Atty.

UNITED STATES PATENT OFFICE.

ALBERT WAGNER, OF CINCINNATI, OHIO, ASSIGNOR, BY MESNE ASSIGNMENTS, TO THE WEMB COMPANY, OF CINCINNATI, OHIO, A CORPORATION OF OHIO.

CARBURETOR.

Application filed February 21, 1922. Serial No. 538,319.

To all whom it may concern:

Be it known that I, ALBERT WAGNER, residing at Cincinnati, in the county of Hamilton and State of Ohio, a citizen of the United States, have invented certain new and useful Improvements in Carburetors, of which the following is a specification.

This invention relates to carburetors which include, as one element, a spray nozzle, and has special reference to the construction of the nozzle whereby the ratio of fuel to air will remain substantially constant at all speeds of the engine. Under ordinary conditions, as the air suction increases as the speed of the engine increases but the flow of fuel increases more rapidly so that while the explosive mixture of air and fuel may be perfect for the normal or average engine speed to which the carburetor is adjusted at higher engine speeds the mixture will be too rich and the operation of the engine will be irregular and uncertain. To overcome this objectionable condition, I have devised a novel construction whereby, as the speed increases, a current of air will be directed against the stream of fuel in opposition to the flow of the same so that the tendency to an augmented flow of fuel will be counteracted and the ratio will remain constant.

In the accompanying drawing, I have illustrated one embodiment of the invention but it is to be understood that I do not limit myself to the exact details of form and arrangement shown as various changes may be made therein without departing from the invention as defined in the claims following this description.

In the drawing,

Figure 1 is a sectional elevation of a carburetor having a preferred form of my invention applied thereto.

Figure 2 is a fragmentary vertical section illustrating the nozzle somewhat enlarged.

Figure 3 is an elevation of the air tube of the nozzle.

Figure 4 is a detail sectional view.

The carburetor comprises a constant level fuel chamber or reservoir 1 which receives the fuel from a supply tank (not shown) in the usual manner, and a mixing tube or chamber 2 connected with the intake of the engine and having an air inlet 3. The mixing tube is shown as having a conduit 4, above the air inlet upon which the nozzle is mounted, and past the sides of which the air

flows. The passage through the conduit 4 establishes communication between the reservoir 1 and the nozzle and also furnishes communication with the idling air inlet 5, said inlet being regulated by a needle valve 6, and the flow of fuel from the reservoir being regulated by adjusting the larger needle valve 7, as will be readily understood. The usual throttle 8 is provided in the mixing tube and the choke valve 9 is provided in the air inlet, while a choke tube 10 is fitted in the mixing tube concentric with the nozzle, as shown in Figure 1.

The nozzle comprises a central nipple 11 rising from a plug 12 which is screwed into the upper side of the conduit 4, the bore of said nipple being in direct communication with the bore of the conduit 4. Disposed concentrically about the fuel jet 11 is an air tube 13 which is also carried by the plug 12 and rises above the nipple 11, the upper end of said jet being below the normal level in the reservoir which is indicated by the line a—a in Figure 1. In the lower portion of the air tube, are longitudinal slots 14, the length of which is less than the height of the nipple 11, and disposed concentrically about the air tube is an emulsion tube 15 which is carried by the plug 12 and may be formed integral therewith, the members 11, 13 and 15 being spaced apart as shown and as will be readily understood. The emulsion tube 15 rises to a somewhat greater height than the nipple 11 and, preferably, its upper end is just above the normal level in the reservoir. The upper end of the air tube is flared, as at 16, and a canopy 17 is supported by the said flared top, inlet openings 18 being provided in the flared top and the under side of the canopy being tapered, as at 19, to properly coat with the inner surface of the flared top of the air tube in deflecting downwardly the entering currents. As shown, the diameter of the canopy should be greater than the outside diameter of the emulsion tube but it should be sufficiently less than the diameter of the mixing tube 2 to permit free flow through the latter.

When the motor is idle the fuel will overflow the nipple 11 and stand in the air tube 13 and emulsion tube 15 to the fuel reservoir level. When the motor starts, fuel only will be drawn from the nozzle through the space between the tubes 13 and 15 until the upper ends of the slots 14 are uncovered 110

whereupon air will be drawn through the air tube and will mix with the escaping fuel. It will be readily noted that the air flowing downward through the air tube will exert a pressure upon the fuel issuing from the nipple 11 in direct opposition to the flow of the fuel so that an excess of the latter in the mixture passing into the engine is prevented. The currents of fuel rising from the tube 15 around and close to the tube 13 will absorb some air and be partly diluted but all of this fuel will not flow to the engine, some of it being intercepted by the deflecting canopy and turned into the air tube through the top of the same. There is thus created a constant circulation of air downward through the air tube and out through the slots therein, this air mingling with the fuel and retarding its escape from the nipple 11 so that the mixture issuing from the emulsion tube 15 will be of the proper quality and proportions to effect successful and economical operation of the engine. Ordinarily, increase in the speed of the engine causes a too rich mixture to be fed thereto as the increased suction causes an increased flow and the volume of fuel passing to the motor increases more rapidly than the volume of air. In my device, however, part of the air supply is directed against the fuel so as to exert a retarding pressure on the issuing liquid which will keep the ratio of the fuel to the air constant. Obviously, the greater the engine speed, the greater will be pressure exerted by the air upon the fuel which is exerting a greater pressure to escape from the fuel nipple. My device is exceedingly simple in the construction and arrangement of its parts and has been found highly efficient in operation.

Having thus fully described my invention, what I claim as new and desire to secure by Letters Patent of the United States is:-

1. In a carburetor, a mixing chamber, an air supply, a liquid fuel supply, means having an inlet located above the normal level of the liquid fuel supply for diverting a part of the air supply and conducting said air supply in opposition to the flow of the liquid fuel supply to an outlet at a point below said normal level. 45
2. In a carburetor the combination of a mixing chamber, an air supply therefor, a liquid fuel supply, and an air tube disposed about the fuel supply, said air tube having an inlet located above the normal level of the liquid fuel supply for diverting a part of the air supply and conducting said air supply in opposition to the flow of the liquid fuel supply to an outlet in the air tube at a point below said normal level. 55
3. In a carburetor the combination of a mixing chamber, an air supply therefor, a liquid fuel supply, and an air tube disposed about the fuel supply, said air tube having an inlet located above the normal level of the liquid fuel supply for diverting a part of the air supply and conducting said air supply in opposition to the flow of the liquid fuel supply to an outlet in the air tube at a point below said normal level, and a deflecting canopy upon the upper end of the air tube, the upper end of the tube being flared and the canopy being of a greater 65 diameter than the flared end and having its under end tapered to deflect air downwardly within the tube. 70

In testimony whereof I hereunto affix my signature.

ALBERT WAGNER.
